COMBINED EAR PIERCING AND EARRING STRUCTURE

Adolph M. Brown, Beverly Hills, Calif.

Application June 12, 1956, Serial No. 41,881

Term of patent 14 years

(Cl. D45—9)

Fig. 1

Fig. 2

Fig. 3

Fig. 4

Fig. 1 is a side elevational view of a combined ear piercing and earring structure embodying the features of this invention in the assembled relation;

Figure 2 is a rear end view thereof;

Figure 3 is a front end view thereof; and

Figure 4 is a side elevational view thereof with the parts in their separated but aligned relation.

I claim:

The ornamental design for a combined ear piercing and earring structure, as shown.
